UNITED STATES PATENT OFFICE.

RICHARD MAX EATON, OF NIAGARA FALLS, NEW YORK, ASSIGNOR TO THE DEAN ELECTRIC COMPANY, OF ELYRIA, OHIO, A CORPORATION OF OHIO.

TELEPHONE METERING SYSTEM.

No. 928,115.

Specification of Letters Patent.

Patented July 13, 1909.

Application filed January 10, 1907. Serial No. 351,715.

To all whom it may concern:

Be it known that I, RICHARD MAX EATON, a citizen of the United States, residing at Niagara Falls, in the county of Niagara and 5 State of New York, have invented certain new and useful Improvements in Telephone Metering Systems, of which the following is a specification, reference being had therein to the accompanying drawing.

10 My invention relates to telephone systems, and especially to means for metering the service afforded subscribers in said systems.

The object of the invention is to provide means which shall record the actual time 15 of use for each telephone as distinguished from the number of times it has been used, thus affording a more equitable basis for charges than has heretofore been possible.

In working out my method and the apparatus therefor, I provide for the use of a 20 percentage of the time record as a basis of charges, this percentage being determined partly by experiments or the known conditions in a given case. I also contemplate de- 25 ducting time which is otherwise charged, such as that consumed in toll or long distance calls, of which record is always made.

Briefly stated, my invention contemplates 30 a timing mechanism, preferably direct reading, located at the subscriber's station, and started in operation every time the receiver is taken down for use. Readings are taken 35 from this mechanism by an inspector the same as in the case of a gas or other meter, and such readings will represent the elapsed time during successive uses of the instrument. The result of this of course will be 40 that time will be charged to the called party as well as the caller, but only, it should be observed, in case the called party answers.

45 As a matter of strict equity, this is correct, for it is only just that each party to the conversation should bear his share of the expense and this falls more heavily in every case on the calling party for the reason that he has his telephone off the hook and his timing mechanism running while the connection is being made and while waiting for the called party to answer. It is proper that 50 this time should be charged against him, since the mechanism is employed by the operator at his demand.

One embodiment of my invention is illus-

trated in the accompanying drawing, in which—

55

Figure 1 is a front view of a telephone wall set containing a timing device, and Fig. 2 is a similar view of the timing device and the switch hook removed from the box. Fig. 3 shows in top view the mechanism of the 60 timing device.

In Fig. 1 B indicates the box or casing containing the telephone parts. Protruding from this box is the usual switch hook H carrying the receiver R; and on the front 65 of the box is mounted the transmitter T. In the upper end of the cover is an opening b which may be glazed or covered with transparent celluloid or the like. Through this opening readings are taken by the inspector. 70

Referring to Fig. 2, h indicates the escutcheon upon which the working parts of the switch hook are mounted. I have shown this escutcheon extended to a sufficient length to carry timing mechanism or clock 75 work C, which is preferably inclosed within a suitable frame work or casing c, and it consists in the several gears 1, 2, 3, 4, 5, 6 supported by arbors 7, 8, 9, as shown in Fig. 3. In front of the casing c appears the end of 80 the main arbor c', having its end squared to permit of winding, and having the usual ratchet connection with the main driving wheel, as indicated in dotted lines. Power is supplied to the train of gears by a weight w, 85 and the accurate running of the mechanism is secured by a scape wheel c³ governed by the escapement c⁴ whose verge rod c⁷ carries the adjustable weight c⁶. The mechanism is normally prevented from running by a 90 spring finger h' attached to the end h² of the stub lever of the switch hook H. The switch hook I have selected for illustration is the same as that shown and described in Letters Patent No. 829,535, granted August 28, 1906, to Ray H. Manson, but the type of 95 switch hook employed is, of course, immaterial.

In operation, when the subscriber removes his receiver R from the hook H, the latter 100 rises and the spring finger h' is removed from contact with the weight c⁶, permitting the latter to vibrate, and thereby permitting the scape wheel c³ to rotate. The rod c⁷ is of course in effect a pendulum, and I contemplate making this entire mechanism quite 105

accurate, so that it may be checked by the subscriber if he desires to do so. As long as the hook H is up, the clock work continues to run, and the graduated wheel or disk c^2 continues to turn. In order to make it direct-reading, I preferably graduate it in hours, and provide a fixed arrow point c^5 on the casing so as to facilitate the reading with exactness.

- 10 While I have shown herein a weight as the actuating means for my time mechanism, and a pendulum or verge rod for the scape wheel, I prefer to use in practice a spring driven motor, and a balance wheel escapement.
- 15 The finger h' or its equivalent, then engages the balance wheel when the hook is down, so as to stop the motor and is removed therefrom when the hook is up, so as to permit it to run.
- 20 My method of operation comprises the reading of all the subscribers' meters, the percentage reduction of these total readings or of the charge per hour, to allow for time lost in various ways, as by calls not answered, and finally the deduction from the total of all charges specifically entered against each subscriber, such as toll or long distance charges. The amount remaining furnishes a just basis for charging the subscriber with his proportionate share of the total charge necessary to be distributed.

Various changes may be made in the arrangement and adaptation of my apparatus, and all such changes I intend to include within the scope of the appended claims.

Having thus described my invention, what I claim and desire to secure by Letters Patent, is:

1. In combination, a plate, a time measuring mechanism and a receiver hook carried by the plate, said receiver hook controlling said time measuring mechanism and a cabinet distinct from the plate for supporting such plate and containing the parts carried thereby.

2. In combination, a mounting plate, time measuring mechanism and a pivoted receiver hook supported by such plate in operative relation to each other, such receiver hook when in its depressed position adapted to prevent operation of the time measuring mechanism and a cabinet distinct from the

mounting plate for supporting such plate and containing the parts carried thereby.

3. In combination, a mounting plate, time measuring mechanism, a movable receiver hook and associated contact springs, such time measuring mechanism, receiver hook and springs carried by such plate, and such receiver hook adapted to permit or prevent operation of the time measuring mechanism according as such hook is in its raised or depressed position and a cabinet distinct from the mounting plate for supporting such plate and containing the parts carried thereby.

4. In combination with a telephone cabinet, a plate, time measuring mechanism and a receiver hook carried by the plate, said receiver hook controlling said time measuring mechanism, said cabinet having an opening therein to permit passing the time measuring mechanism and receiver hook therethrough whereby said time measuring mechanism and receiver hook may be supported within the cabinet by the plate.

5. In combination with a telephone cabinet, a plate, time measuring mechanism carried by the plate, a movable receiver hook controlling said time measuring mechanism and so supported from the plate as to pass therethrough, contact springs associated with the receiver hook and carried by the plate, said cabinet having an opening therein to permit passing therethrough the parts carried by the plate, whereby the time measuring mechanism, receiver hook and contact springs may be supported within the cabinet by the plate.

6. In combination with a telephone set, a receiver, a receiver hook, time measuring mechanism associated with the hook, means independent of the hook for driving such mechanism, an escapement for such mechanism, and means carried by the hook for engaging such escapement to prevent operation of such mechanism when the receiver is on the hook.

In testimony whereof I affix my signature in presence of two witnesses.

RICHARD MAX EATON.
